UNITED STATES PATENT OFFICE.

WILSON D. HAVEN, OF TRENTON, NEW JERSEY.

STEAM-ENGINE VALVE.

SPECIFICATION forming part of Letters Patent No. 415,385, dated November 19, 1889.

Application filed October 29, 1888. Serial No. 289,426. (No model.)

To all whom it may concern:

Be it known that I, WILSON D. HAVEN, a citizen of the United States, residing at Trenton, in the county of Mercer and State of New Jersey, have invented certain new and useful Improvements in Steam-Engine Valves; and I do declare the following to be a full, clear, and exact description of the invention, such as will enable others skilled in the art to which it appertains to make and use the same.

My invention is directed to securing a greater accuracy of travel and greater durability in steam-engine valves; and to this end it consists in certain parts and combinations of parts hereinafter more particularly set forth.

My invention relates to a construction of supporting and guiding devices of the valve-stem by which the valve is more accurately balanced, its bearing equalized, and vibration of the valve-stem and valve prevented.

My invention also relates to a construction of the valve-ports by which the weight of the valve is carried by the steam-pressure and relieved from the lower part of the valve-seat, thereby rendering the wear upon all parts of the circumference of the valve and case equal.

In order to make my invention more clearly understood, I have shown in the accompanying drawings means for carrying the same into effect.

In said drawings, Figure 1 is a side view, partly in section, of so much of a steam-engine as is necessary to illustrate my invention. Fig. 2 is a longitudinal section on a larger scale of a simple form of the outboard-bearing for the valve stem. Fig. 3 is a cross-section on line 3 3 of Fig. 2. Fig. 4 is a cross-section on line 4 4 of Fig. 1.

Referring to the drawings, A indicates the steam-engine cylinder; B, the valve-gear; C, the valve-stem; D, the valve-case or steam-chest into which the live steam enters, as indicated by the arrows, and E the valve or valves mounted therein and secured to and actuated by the valve-stem C.

In the construction illustrated the valves are both oscillating and reciprocating; but such combined movements are not essential to obtaining all of the advantages of my in-

vention. The reciprocation of the valve regulates the exhaust by way of passages e, while the oscillation of the valve admits and cuts off the steam in a well-known manner. 55 Where the steam-admission ports of the valve are in the form of long slits or openings, I have found that an unequal wear and chattering of the valve in its seat takes place, due to the slight expansion of the hollow 60 shell of the valve and the forcing out of the edges of the ports so made. I have obviated this difficulty to a considerable extent by forming the ports, as shown at a, with one or more cross-bridges a', adapted to maintain 65 the proper cylindrical shape of the valve, prevent the forcing outward of the edges of the port, and unequal wear and chattering in the valve-seat, resulting finally in a materially greater durability of these parts. 70

At the end of the valve-case next to the valve-gear there is formed the usual stuffing-box d for the passage of the valve-stem from the interior of said case to the valve-gear, which box forms a guide and support for one 75 end of the stem and valve.

I have discovered by practical experiment that the peculiar movements of the valve and stem incident to the use of the special valve-gear shown have a very objectionable and 80 serious effect in cutting away the valve, stem, and casing. I have, however, been able to obviate these serious results by combining with said valve-gearing what may be termed an "outboard-bearing," which I will now describe, first referring, however, more particularly to the valve-gear above mentioned. This gear was first described in Letters Patent No. 339,814, granted April 13, 1886, to F. Schumann and myself. It comprises, essentially, a 85 rock-lever or equivalent moving part E⁴, connected with the valve-stem for reciprocating it, a bell-crank lever G⁴, mounted upon a pivot g¹⁴, carried by said part E⁴, a means—such as a governor-rod H⁴—for oscillating the bell-crank lever relative to part E⁴, and connections—such as the rod J⁴ and arm D⁴—between the other end of the bell-crank lever and the valve-stem for oscillating the latter and the valve. This mechanism causes a 90 screw-like movement of the valve, which is, however, unequal, being rapid or accelerated 95 100

at one point, resulting in a serious deterioration of the valve and case. This I have obviated, as above stated, by combining with said valve-gear and valve the following guiding and supporting means.

Referring more particularly to Figs. 2 and 3, G indicates the head of the valve-case, detachably secured in any suitable manner, as by the hooked bolts g. This head is provided with a cylindrical sleeve G', extending in a direction or directions parallel with the valve-stem. g'g' indicate a two-part bushing mounted in the sleeve G', and of such interior diameter as to properly fit the exterior of the valve-stem. The lateral edges of the two parts of the bushing do not touch, but are arranged to leave spaces, as shown in Fig. 3, to permit of the lower half of the bushing being from time to time adjusted upward to compensate for the wear which takes place between said lower half and the stem. This adjustment is provided for by the screws g², which are tapped into the under side of the sleeve G' and bear against the lower half of the bushing g'. g³ is a ring fitting in the inner end of the sleeve G', and having between it and said bushing a space g⁴ for the reception of a suitable packing. The sleeve and bushing above described are of such length as to permit the necessary reciprocation of the valve-stem, and as a finish and to shut out from view the moving end of said stem I provide the outer end of the bearing with a cap G², which is adapted to be secured upon the sleeve G'.

The bearing above described serves to balance the valve-stem by exposing to the outer air at this end of the valve-case an area equal to that of the cross-section of the valve-stem at the end next the valve-gear. To this end the cap G² is provided with an opening g⁴, through which atmospheric pressure acts upon the end of the stem.

In order to further take off wear from the under side of the valve and stem, I have constructed the upper port or ports of the oscillating valve-shell of a slightly less area than that of the lower port or ports. Referring to Fig. 4, it will be seen that of the four steam-ports a shown in the construction there illustrated those at the upper side of the valve are the smaller. As this difference is in practice of small account, I have indicated the larger ports by the letters y y and the smaller ports

by the letters x x. The difference in area will be proportionate to the weight of the valve and to the steam-pressure under which the engine is constructed and adjusted to run, and will of course vary in different engines. The result of this construction is that the weight of the valve and stem may be entirely sustained by the live-steam pressure and the friction and wear between the moving and stationary parts much diminished.

Having thus described my invention, what I claim is—

1. In an engine, the combination, with the valve, valve-stem, and casing, of a moving part—such as lever E⁴—for reciprocating the valve, a bell-crank lever mounted upon a pivot carried by said part, means for oscillating the bell-crank lever relative to said moving part, connections between the bell-crank lever and the valve for oscillating the latter, and an outboard-bearing situated at the end of the valve opposite said valve-gearing and supporting the valve-stem, substantially as set forth.

2. The combination, with the valve, the valve-stem, and the valve-casing provided with the stuffing-box and bearing d, of the outboard-bearing provided with the bushing g', divided horizontally, as described, and adjusting devices for raising the lower half of said bushing, substantially as set forth.

3. The combination, with the valve, the valve-stem, and the valve-casing having the bearing d, of the outboard-bearing at the opposite end of said casing, consisting of a sleeve G', flanged and divided bushing g', and the cap G², fitting and secured to the end of said sleeve and securing the flanges of said bushing between itself and said sleeve, substantially as set forth.

4. The combination, with the valve-casing having ports on its upper and under sides, of the hollow valve provided with corresponding ports adapted to simultaneously open and admit steam to the cylinder through both the upper and under ports, the upper of said valve-ports being of smaller area than the lower, substantially as set forth.

In testimony whereof I affix my signature in the presence of two witnesses.

WILSON D. HAVEN.
